UNITED STATES PATENT OFFICE.

OLIVER McCARTHY, OF MERIDEN, CONNECTICUT, ASSIGNOR TO THE
MERIDEN BRITANNIA COMPANY, OF SAME PLACE.

DESIGN FOR A COFFIN-HANDLE ARM.

SPECIFICATION forming part of Design No. 16,893, dated September 7, 1886.

Application filed July 26, 1886. Serial No. 209,181. Term of patent 7 years.

To all whom it may concern.

Be it known that I, OLIVER McCARTHY, of Meriden, in the county of New Haven and State of Connecticut, have invented a new Design for Coffin-Handle Arms; and I do hereby declare the following, when taken in connection with accompanying drawings and the letters of reference marked thereon, to be a full, clear, and exact description of the same, and which said drawings constitute part of this specification, and represent, in—

Figure 1, a face view of the arm; Fig. 2, a transverse section cutting on line *x x*.

This invention relates to a design for the coffin-handle arm; and it consists in the configuration of the arm, as shown in the accompanying illustrations, and hereinafter described.

In the illustrations, I show the socket in broken lines.

A represents the handle-bar. These parts are introduced for the better understanding of the design. At the lower part of the arm the two sides are parallel, and to a sufficient extent to cover the bar. From this point the sides curve inward, and then run substantially parallel to the top. Upon the face of the arm is a raised rib, *a*, the two edges of which start

from each side of the lower end and curve inward to about midway of the length of the handle, and then curve outward to the respective outer edges at the upper end of the handle, the surface from the rib to the right and left concave in transverse section, as seen in Fig. 2. The lower end of the handle terminates in a tip, here represented as of semi-cylindrical shape; but the tip may be varied without departing from this design.

I claim—

The herein described design for coffin-handle arm, having its two sides parallel from the lower end upward for a part of the length of the arm, then contracted by a curve into a narrower width, and presenting substantially parallel sides to the upper end, with the representation of a rib, *a*, on the face, the sides of which curve from each side of the lower end of the arm inward to about midway of the length of the arm, thence outward to the corresponding sides at the top, as shown in the accompanying illustration.

OLIVER McCARTHY.
